UNITED STATES PATENT OFFICE.

JOSEPH J. MIZER, OF RACINE, WISCONSIN, ASSIGNOR TO WALKER MANUFACTURING COMPANY, OF RACINE, WISCONSIN, A CORPORATION OF WISCONSIN.

LIFTING JACK.

Application filed November 7, 1921. Serial No. 513,342.

To all whom it may concern:

Be it known that I, JOSEPH J. MIZER, a citizen of the United States, residing at Racine, in the county of Racine and State of 5 Wisconsin, have invented certain new and useful Improvements in Lifting Jacks, of which the following is a specification.

My invention relates to lifting jacks, and particularly to the arrangement and construction of the lifting lever. It is the principal object of my invention to provide a simple and efficient construction by which the lifting pawl is pivotally mounted on the lifting lever upon an axis in close proximity 10 to the axis of the lever, the mounting of both parts being effected by the use of a steel pin which provides the desired strength and durability. It is another object of my invention to improve devices of this type in 15 sundry details hereinafter pointed out. The preferred means by which I have accomplished my several objects are illustrated in the drawings and are hereinafter specifically described. That which I believe to be 20 new and desire to cover by Letters Patent is 25 set forth in the claims.

In the drawings,—

Fig. 1 is a vertical section through a lifting jack embodying my improved construction.

Fig. 2 is a vertical section through the pivot end of the lifting lever, showing the lifting pawl mounted thereon so as to be supported on the pivot pin of the lever.

Fig. 3 is a vertical section taken on line 3—3 of Fig. 2, and

Fig. 4 is a perspective view of the lifting pawl.

Referring to the several figures of the drawings in which corresponding parts are indicated by the same reference characters, 40 10 indicates a standard in the form of a housing rising from a base 11, in the construction shown the standard and base being 45 in the form of an integral casting. Slidably mounted within the housing 10 is a rack bar 12 provided at its upper end with a weight supporting head 13 of any approved type, in the construction shown the 50 rack bar 12 and the head 13 being formed integrally by casting. A holding pawl 14 of any approved type is pivotally mounted by means of a pin 15 in the housing 10 in position to engage the teeth of the rack bar

12 for holding the rack bar in a raised 55 adjusted position.

As is clearly shown in Fig. 1, the housing 10 is provided with a slot 16 at one side thereof for insertion of the lifting lever which is of any approved type, in the construction shown being in the form of a hollow casting 17 at its lower end having a handle or bar 18 mounted in its outer end. As is clearly shown in Fig. 1, the casting 17 is provided with a groove or offset 60 portion 19 at its upper edge which is adapted to embrace the lower end of the holding pawl 14, the provision of the groove serving to increase the throw of the lever as is indicated by the dotted line position 65 of the lever in Fig. 1.

Coming now to the means for mounting the lever 17 in position, 20 indicates a pivot pin extending through a suitable circular opening through the end of the lever, the 70 ends of the pin being extended at both sides of the lever for support within suitable bearings 21 provided by the housing 10, as is shown in Fig. 3. The pin 20 is 75 designed to be formed of hardened steel for 80 providing a support of great strength and great durability for the lifting lever. For providing for the mounting of the lifting pawl 22 in proximity to the axis of the lever 17, I have provided a rounded 85 groove 23 in one side portion of the pin 20 which is adapted to receive the rounded end of the pawl 22 so as to provide a support therefor. In the construction shown the pawl 22 is pivotally mounted in position 90 by means of circular disks 24 mounted in the groove 23 at opposite sides of the pawl 22, the disks 24 being provided auxiliary support by suitable bearings in the wall portion of the casting 17. As is best shown 95 in Fig. 3, the disks 24 and the end of the pawl 22 are perforated to provide for the insertion of a pintle 25 by which the pawl 22 is pivotally supported in position. As is shown in Fig. 2, the pin 20 is cut away 100 at one side adjacent to the groove 23, as is indicated at 26, for permitting the pawl 22 to move to the desired limit of motion with respect to the lever 17. For holding the pin 20 against rotation with respect to the lever 17 for the purpose of preventing binding 105 of the pawl 22 with respect to the pin 20, I have provided a key 27 mounted in a

suitable opening in the pin and the casting 17.

By the use of my construction as above described, I have provided a strong and efficient mounting for the lifting pawl upon the lifting lever. I have not deemed it necessary to show in the drawings or to describe herein the means for effecting cooperation between the lifting lever, the lifting pawl 10 22, and for the holding pawl 14. It will be understood that any appropriate means may be provided for this purpose.

I claim:

1. In a lifting jack, the combination of a lifting lever having an opening for the reception of a pivot pin, a pin cut away at one side and inserted in said opening, and a lifting pawl pivotally mounted in position to contact said pin at its cut-away portion for 20 partial support by the pin.

2. In a lifting jack, the combination of a lifting lever having an opening for the reception of a pivot pin, a pin cut away at one side and inserted in said opening, and a lifting pawl pivotally mounted on said lever in position to contact said pin at its cut-away portion for partial support by the pin.

3. In a lifting jack, the combination of a lifting lever having an opening for the reception of the pivot pin, a pin having a rounded groove cut in one side portion and mounted in said opening, and a lifting pawl having its end curved to conform to the curvature of said groove pivotally mounted in 35 position in said groove for partial support thereby.

4. In a lifting jack, the combination of a lifting lever having an opening for the reception of the pivot pin, a pin having a rounded groove cut in one side portion and mounted in said opening, and a lifting pawl having its end curved to conform to the curvature of said groove pivotally mounted in 40 position in said groove for partial support

thereby, said pin being further cut away adjacent to said rounded groove for permitting the pawl to move to the desired limit of motion with respect to the lever. 45

5. In a lifting jack, the combination of a lifting lever having an opening for the reception of a pivot pin, a pin cut away at one side and inserted in said opening, a lifting pawl pivotally mounted in position to contact said pin at its cut-away portion for partial support by the pin, and means for holding said pin against turning with respect to the lever for preventing binding between the lever and the pawl. 50

6. In a lifting jack, the combination of a lifting lever having an opening for the reception of a pivot pin, a pin having a rounded groove cut in one side portion and mounted in said opening, a lifting pawl having its end curved to conform to the curvature of said groove pivotally mounted on the lever 65 in position to engage said groove for partial support thereby, and a key mounted in contact with said pin for holding the pin against turning with respect to the lever for preventing binding between the lever and 70 the pawl.

7. In a lifting jack, the combination of a lifting lever having an opening for the reception of a pivot pin, a pin having a rounded groove cut in one side portion and mounted in said opening, a lifting pawl having its end curved to conform to the curvature of said groove, and means for pivotally mounting said pawl in position in said groove for partial support thereby, said means comprising circular disks mounted in said groove at opposite sides of the pawl, and a pintle mounted in registering openings through said disks and said pawl, said disks being additionally supported by bearings in said 75 lever. 80

JOSEPH J. MIZER.
